CLAIM

The ornamental design for a combined print liquid supply cap and key, as shown and described.

DESCRIPTION

FIG. 1 is a front, top, and first side perspective view of a combined print liquid supply cap and key showing a new design;

FIG. 2 is a rear, top, and first side perspective view thereof;

FIG. 3 is a front elevation view thereof;

FIG. 4 is a rear elevation view thereof;

FIG. 5 is a second side elevation view thereof;

FIG. 6 is a first side elevation view thereof;

FIG. 7 is a top plan view thereof; and,

FIG. 8 is a bottom plan view thereof.

The broken lines immediately adjacent to the shaded areas depict the bounds of the claimed design, while all other broken lines are directed to environment. The broken lines form no part of the claimed design.

1 Claim, 6 Drawing Sheets
